UNITED STATES PATENT OFFICE.

FRANK R. PACKHAM, OF SPRINGFIELD, OHIO.

METAL-CRIMPING MACHINE.

SPECIFICATION forming part of Letters Patent No. 369,876, dated September 13, 1887.

Application filed January 12, 1887. Serial No. 224,164. (No model.)

To all whom it may concern:

Be it known that I, FRANK R. PACKHAM, a citizen of the United States, residing at Springfield, in the county of Clark and State of Ohio, have invented certain new and useful Improvements in Metal-Crimping Machines, of which the following is a specification.

My invention relates to metal-crimping machines, and particularly relates to that class of machines adapted to crimp the ends of stove-pipes, bucket-lids, &c., to produce a taper thereon.

It also relates in its nature to improvements on the machine described and set forth in my Letters Patent No. 349,355, of September 21, 1886.

My invention consists, first, in a novel arrangement for supporting the upper roll, whereby the said roll may be moved bodily to vary the depth of the serrations or crimps produced thereby, means being provided for varying the angle of said roll to secure a variation in the taper produced thereby.

My invention further consists in a novel arrangement for securing the rolls on the respective shafts or either of them, so that the ends of said rolls will stand flush with the ends of the said shafts in crimping bucket-lids and similar articles.

My invention further consists in various constructions and arrangement of parts herein-after described, and pointed out in the claims.

In the accompanying drawings, which form part of this specification, Figure 1 is a side elevation of a device embodying my invention, the side cover or bearing-plate being removed therefrom. Fig. 2 is a sectional elevation of the same on the line *xx*. Fig. 3 is a side elevation showing the respective parts in a different position of adjustment, some of the parts being modified slightly in construction, as hereinafter more fully set forth. Fig. 4 is a sectional view of the same on the line *yy*. Fig. 5 is an inside view of the upper-roll-supporting device and the side cover in an inverted position. Fig. 6 is a sectional view of the same on the line *zz*. Figs. 7 and 8 are detail views of the end of the main shaft and roll, showing the method of removing or securing said roll in place.

In the accompanying drawings, A represents the main frame, which is provided near the bottom thereof with a bearing, *a*, for the main

shaft B and with an upwardly-extending side wing, *a'*. Supported on the side wing, *a'*, in 55 the manner hereinafter more fully described, is the upper-roll-supporting device C, provided with a suitable shaft or journal, *b*, for the crimping-roll C' and the ogee or beading roll C². The corresponding lower rolls, B' and 60 B², are supported on the main shaft B, and are revolved thereby, in a manner hereinafter more fully described. The crimping-rolls B' and C' are preferably made of uniform size and provided with a series of serrations of a 65 uniform depth throughout, the gradually-decreasing depth of serrations formed by the machine in operation, thus producing the taper, being secured by placing the respective shafts at an angle, the length of the taper being varied by the variations in the angle of the shaft. 70

Means are provided for moving the upper roll to and from the lower roll to introduce and remove the work therefrom and to graduate the depth of the flutes or serrations to be formed. In the machine set forth in my above-mentioned patent this was accomplished by having the upper-roll-supporting device pivoted at the rear end, means being provided 80 for changing the position of the pivot in order to change the angular position of the crimping-rolls. In my present machine I dispense with the use of the pivot and provide a movable side or bearing plate on which the upper-roll-supporting device is adapted to move, means being provided by which the position of the side or bearing plate may be changed to change the angular position of the roll supported thereby. This I preferably accomplish as follows: The upper-roll-supporting device C is provided at the rear end with a frame, *b'*, which is provided on each side with projecting lugs or bearings *b²*, adapted to rest, respectively, against the side wing, *a'*, and the 85 side or bearing plate, D. This side or bearing plate, D, is provided with projecting ribs *c*, adapted to fit snugly in the frame *b'*. The side or bearing plate, D, is secured to the side wing, *a'*, by means which will permit it to be 90 turned to different positions thereon, thus turning the upper-roll-supporting journal and varying the angle thereof in relation to the main shaft B. This may be accomplished by providing on the side or bearing plate, D, a 95 small projection, *c'*, adapted to extend into an

opening, a^2 , in the side wing, a' , and a screw-threaded stud, c^2 , adapted to extend through a slotted opening, a^3 , in the said side wing. A thumb-nut, c^3 , is provided on the end of the 5 said stud, by means of which the bearing-plate D may be firmly secured in any desired position of adjustment on the side wing, a' . The bearing-ribs c are made slightly longer than the depth of the frame b' , so that when the 10 bearing-plate D is drawn tightly against the side wing, a' , the frame b' will move freely thereon. (See Fig. 6.)

Located in the frame b' , and resting at one 15 end against the side of said frame and at the other against a projecting lug, a^5 , on the side wing, a' , is a spring, b^3 , adapted to press the supporting-frame and its roll upwardly, thus holding the roll C' out of engagement with the roll B'. Immediately above the spring 20 b^3 and adapted to bear on the top of the supporting-frame b' is an adjusting-screw, d , by means of which the engagement of the rolls C' and B' may be graduated as desired. It will be seen that by this construction the upper roll may be moved to or from the lower roll, as desired, the movement being accomplished uniformly at each end of the roll. By changing the position of the bearing-plate the angular position of the rolls may be readily 25 changed as desired, after which any depth of flute or serration may be formed in the article operated upon without varying the angularity or taper thereof.

The lower main shaft, B, I make of a uniform size throughout, so that it may be moved longitudinally in the main bearing a . This shaft B projects at the rear and is provided with a handle, E, preferably secured thereon by a set-screw, e.

40 In order that the rolls may be readily removed when desired, and to provide for securing the crimping-roll flush with the end of the shaft when the ogee or beading roll is removed for the purpose of crimping bucket-lids or similar articles, I provide in the shaft B small holes or pockets f , adapted to receive small removable pins f' . In the ends of the respective rolls I provide small depressions or sockets f^2 , into which the pins are adapted to 50 enter.

The handle E is adapted to bear against the rear end of the main bearing a . The roll B' is adapted to bear against the front end of the bearing a . When the handle is secured on the 55 shaft B, the said shaft is held against longitudinal movement through its bearing. By loosening the set-screw, however, the shaft may be moved longitudinally sufficiently to withdraw the pins f' from the sockets f^2 , after 60 which the pins f' may be removed from the shaft B, allowing the rolls to be changed as desired. By removing the ogee or beading roll and replacing the pins f' in the outer hole in the shaft B, the said shaft may be slipped 65 through its bearing until the pin f' engages in the socket of the crimping-roll B'. The han-

dle E is moved forward on the shaft until it comes against the bearing a , after which it is again secured in place, thus leaving the outer end of the crimping-roll flush with the shaft 70 and unencumbered for crimping short flanges or similar articles. I preferably provide in the rear end of the shaft B a small groove or keyway, e' , in which the end of the set-screw is adapted to enter, so that the handle E may 75 be held against revolution on the said shaft.

In ordinary cases it is only necessary to have one of the crimping-rolls flush with the end and adjustable with its supporting-shaft, though it is obvious that either or both of the 80 supporting-shafts may be made longitudinally adjustable, as set forth in my patent, September 21, 1886, above referred to.

In Fig. 3 I have shown the upper-roll-supporting device C provided with a socket, b^5 , 85 having a thumb-screw, b^7 , by which the shaft b may be readily adjusted longitudinally and held in any desired position of adjustment. In Fig. 3 I have also shown the construction of the bearing-plate D slightly modified, the 90 projection c' being dispensed with, the plates being adapted to be adjusted by the stud c^2 , which extends through a circular opening in the side wing, a' , and forms a pivot for said plate. The plate D is held in different positions of adjustment by tightening the thumb-nut c^3 . In this case it may be desirable to provide the face of the side wing, a' , and one of the bearing-ribs c with a series of serrations, g , (see Figs. 3 and 4,) by means of which the 95 plate D will be held securely from turning when the thumb-nut c^3 is tightened. In this construction the spring b^3 , which serves to move the frame b' , is supported directly on the stud c^2 , as shown in Fig. 4.

It is obvious that various other modifications may be employed without departing from the spirit of my invention.

I preferably provide each of the crimping-rolls with a small groove, h , which extends 100 around its periphery, cutting the flutes or serrations therein, and I arrange the gage F so that the work inserted between the rolls never comes beyond the said groove. By this construction that portion of the roll which is inside of the groove h is protected from wear and serves the purpose of transmitting motion to the upper roll in case the roll becomes much worn by use.

Having thus described my invention, I 110 claim—

1. In a crimping-machine, the combination, with the intermeshing rolls, of a roll-supporting device adapted to support one of said rolls normally at an angle to the other, means for changing the relative angular position of the said rolls, and means for moving one of the said rolls to or from the other roll without changing the relative angular position of the said rolls, substantially as specified.

2. In a crimping-machine having the intermeshing rolls, a bearing-plate adapted to sup-

port the shaft or journal of one of said rolls in such a manner that it may be moved bodily to and from the axis of the other roll, and means for securing said bearing-plate in different angular positions to vary the axial angle of said rolls, substantially as set forth.

3. In a crimping-machine, the main frame provided with a bearing for the main shaft on which one of the crimping-rolls is secured, an adjustable supporting-frame carrying a shaft or journal on which the other roll is supported, a bearing-plate secured to said main frame, on which the supporting-frame is adapted to reciprocate, means for moving said supporting-frame in relation to the said bearing-plate, and means for securing the said bearing-plate in different positions on the said main frame, substantially as and for the purpose set forth.

4. In a crimping-machine having the intermeshing rolls, a main frame provided with a lower bearing and an upwardly-extending side wing, a bearing-plate secured to said side wing, a supporting-frame carrying one of the said rolls, and means for moving said supporting-frame bodily on said bearing-plate, substantially as set forth.

5. In a crimping-machine, the main frame provided with a bearing for the main shaft, on which one of the crimping-rolls is secured, a bearing-plate on the said main frame, and a supporting-frame on the said bearing-plate, said supporting-frame being adapted to support the other crimping-roll at an angle to the main shaft, and means for moving said supporting-frame and its crimping-roll bodily to and from the main shaft without changing the angular relation of the said rolls, substantially as set forth.

6. In a crimping-machine, the main frame provided with a lower bearing and an upwardly-extending side wing, the main shaft in said bearing supporting one of the crimping-rolls, and a movable supporting-frame provided with a shaft or journal for the other crimping-roll, a bearing-plate secured to the said side wing and provided with bearing-ribs on which the supporting-frame is adapted to slide, means for moving the supporting-frame in either position on the said bearing-plate, and means for securing the said bearing-plate in different angular positions on the said side wing, substantially as set forth.

7. In a crimping-machine, the main frame provided with a lower bearing and an upwardly-extending side wing, the bearing-plate provided with ribs bearing on the side wing, said bearing-plate being provided with a stud projecting through said side wing and having a clamping-nut thereon, the supporting-frame on the said bearing-ribs, provided with a shaft or bearing for one of the crimping-rolls, the main shaft supporting the other crimping-roll, located in the main bearing in said frame, and means for moving the supporting-frame to and from the main shaft in an angular position, substantially as set forth.

8. In a crimping-machine, the main shaft supporting one of the crimping-rolls, said shaft being adapted to move longitudinally through the bearing in which it is adapted to revolve, a removable pin or stud in said shaft adapted to engage a socket in the roll thereon, and means for securing said shaft in different positions of longitudinal adjustment in said bearings, substantially as set forth.

9. In a crimping-machine, the main shaft adapted to be moved longitudinally in the bearing, in which it is also adapted to revolve, a crimping-roll on the said shaft, and a pin or stud adapted to engage a socket in said crimping-roll when the end of said crimping-roll is flush with or beyond the said shaft, substantially as set forth.

10. The main frame provided with a bearing for the main shaft, which is adapted to be moved longitudinally through said bearing, a removable pin in said shaft, a crimping-roll provided with a socket on the said shaft, and means for securing the said shaft in different positions of longitudinal adjustment, substantially as set forth.

11. In a crimping-machine, the longitudinally-moving main shaft supporting one of the crimping-rolls, said shaft being provided with a removable pin adapted to engage a socket in said crimping-roll, a supporting-frame provided with a shaft or journal for the other crimping-roll, means for moving said supporting-frame bodily to and from said main shaft, and means for securing the said main shaft in different positions of longitudinal adjustment, substantially as and for the purpose set forth.

12. The combination, with the main frame, of the bearing-plate provided with bearing-ribs thereon, the supporting-frame adapted to slide on the said bearing-ribs, an adjusting-screw for moving said supporting-frame in relation to said bearing-plate, and a spring adapted to move said supporting-frame in opposition to said adjusting-screw, substantially as set forth.

13. The combination, with the main frame having the adjustable bearing-plate thereon, and a movable supporting-frame carrying one of the crimping-rolls, supported on said bearing-plate, of a longitudinally-moving shaft journaled in said main frame, supporting the other crimping-roll, a removable pin or stud in said shaft adapted to engage with the roll thereon, and means for permitting a longitudinal movement of said shaft through its bearings, substantially as and for the purpose set forth.

In testimony whereof I have hereunto set my hand this 7th day of January, A. D. 1887.

FRANK R. PACKHAM.
